UNITED STATES PATENT OFFICE.

PERRY E. BURNHAM, OF SALT LAKE CITY, UTAH.

WATER-MEASURING DEVICE.

1,259,076.

Specification of Letters Patent.

Patented Mar. 12, 1918.

Application filed April 14, 1917. Serial No. 162,205.

To all whom it may concern:

Be it known that PERRY E. BURNHAM, a citizen of the United States, residing at 880 East First South, Salt Lake City, in the county of Salt Lake and State of Utah, has invented certain new and useful Improvements in Water-Measuring Devices, of which the following is a specification.

This invention relates to a device for accurately measuring the flow of water and its object is to provide an improved structure of this character adapted to be disposed at any desired point in a canal, ditch or the like, of any size, shape or character of banks and capable of accurately indicating the flow of water therethrough.

A further object of the invention is to provide a device of the character above set forth constructed in such manner as to adapt it to serve as a head gate as well as a measuring device.

A further object of the invention is to provide a device of the character above set forth constructed in such manner as to adapt it to measure water in a channel having a very slight grade.

As this description proceeds it will be seen that the device forming the subject-matter thereof may be manufactured at a moderate cost and in such manner that it will not be subject to drying and swelling, warping and cracking, with resultant leakage and that consequently the expense of maintenance of the same is reduced to a minimum.

35 In the accompanying drawing,

Figure 1 is a perspective view of a combined head gate and measuring device constructed in accordance with the invention.

Fig. 2 is a vertical, sectional view through the gate thereof, and

Fig. 3 is a horizontal, sectional view through the gate thereof.

In the drawing *u* designates a metal box which may be of any desired shape in cross section and the several parts of which are securely riveted together as indicated at *q* to provide a structure that will be water tight except for the orifice or inlet opening *a* and the discharge opening *b*. *m* indicates a lap joint made in the metal *l* of the box by which the entire vertical portion of the box *u* is fastened together. The box comprises a bottom *n* secured by a joint *o* to the side walls.

55 To aid in stiffening and reinforcing the structure angle irons *k* are secured thereto

about the outer edges thereof. A discharge pipe *p* leads from the discharge opening *b* and the flow of the water from the interior of the box *u* to the discharge pipe *p* is controlled by a gate *c*. A bar *d* having a plurality of openings *s* formed therein is connected at its lower end to the gate *c* and pivotally connected at its upper end to a lever *e*. One end of this lever is pivotally connected to one of the pair of vertical angle irons *f* secured to the rear wall of the box *u*. By means of the openings *s* and oblique openings *t* formed in one of the angle irons *f* the gate *c* may be adjusted vertically to any desired point and securely held in adjusted position. The lower end of the bar *d* is provided with a wedge-like projection *j* which cooperates with the transverse angle iron *g* to force the top of the gate toward the rear wall of the box when the gate is at its lowermost position. The lower end of the gate is likewise forced toward the rear end of the box at this time by means of an inclined plate *h*. This construction insures a tight fit between the gate *c* and the rear wall of the box while still rendering it possible to use sheet metal parts.

This is highly desirable because sheet metal is not subject to the shrinking and swelling and warping and cracking which have been found so highly objectionable in the use of wooden parts for this purpose.

Guides *i* receive the side edges of the gate *c* (see Fig. 3) and hold the gate in its proper course of travel. The lower edge of the discharge opening *b* is level with the highest point of the inlet opening *a*, thus insuring complete submersion of the opening *a* as long as there is any flow through the discharge pipe *p*.

A pair of galvanized iron pipes of the same length are soldered together and held vertically alongside of the box *u* by means of strips *Z*. These pipes extend from a point level with the center of the inlet opening *a* to the top of the box and they carry floats *V* and *W* which rise and fall in the pipes with the rise and fall of the water levels on the outside and inside of the box, respectively. The water pressure outside of the box *u* is communicated to the float *V* through the bottom of said pipe, the bottom of said pipe being open, while the water pressure inside of the box is communicated to the float *W* through an opening *z* formed in the side wall of the box *u* the pipe *x* in

which the float W is located having a closed bottom.

Two small vertical wires y are attached to the floats, said wires being of such length 5 that when the water levels within and without the box are at the same elevation the tops of the wires will be at the same elevation.

In use the apparatus herein shown and 10 described is located in the bank of the canal which furnishes the supply of water and in such a position as to secure a continuous submersion of the orifice and the free passage of the water of the canal into the pipe carrying the float V. The height of the box is made to correspond to the depth of the canal. With the gate c closed the water will stand at the same level inside the box as in 15 the canal outside of the box and the tops of the wires y will be at the same elevation. As the gate c is raised and varying quantities of water allowed to pass through discharge pipe p and thence through a ditch or elsewhere, there results a corresponding difference of level in the water surface inside 20 of the box and in the canal and this difference is indicated by the difference in elevation of the tops of the wires y. This difference of water level is due to the "loss of 25 head" in passing through the inlet opening a.

Having once ascertained the rate of flow during any given difference in elevation of the tops of the wires y, it follows that a 30 rating table may be had which in conjunction with the wires y will render it possible to determine the amount of water passing the gate at any given time.

It will, therefore, be observed that in addition to providing a measuring means as 35 herein set forth my improved structure serves the function of a head gate and that by its use the entire flow of water may be controlled or shut off at will.

From the foregoing description it will be 40 seen that simple and efficient means are

herein provided for accomplishing the objects of the invention but while the elements shown are well adapted to serve the purposes for which they are intended it is to be understood that the invention is not limited to the precise construction set forth but includes within its purview such changes as come within the spirit of the appended claims. 55

Having described my invention what I claim is:—

1. The combination with a receptacle of a pair of stilling wells, one of which wells is in communication with the water outside of the receptacle and the other of which is in communication with the water on the inside of the receptacle, a float in each well, a rigid upstanding rod carried by each float, said rods lying side by side and coöperating 60 indicating members carried directly by said rods and movable therewith in respect to each other. 65

2. A device of the character described comprising a compartment, an inlet opening 70 thereto, an outlet opening therefrom, a gage comprising a pair of elements one of which is actuated under the influence of the water within the compartment and the other of which is actuated under the influence of 75 the water outside of said compartment, the difference in movement of said elements indicating the difference in the water levels inside and outside of said compartment, respectively, and a gate for controlling the 80 passage of water from said compartment through the outlet openings. 85

3. A structure as recited in claim 2 wherein in the lowest point of said outlet opening is at least as high as the highest point of the inlet opening.

In testimony whereof I affix my signature in the presence of two witnesses.

PERRY E. BURNHAM.
